UNITED STATES PATENT OFFICE

2,500,504

THERMIONIC VALVE CIRCUITS

John J. Antalek, Chicago, Ill., assignor to The Rauland Corporation, Chicago, Ill., a corporation of Illinois

Application April 23, 1945, Serial No. 589,784

9 Claims. (Cl. 250—27)

1

This invention relates to thermionic valve circuits and especially to amplifier circuits supplying a dial illuminating device or any other discontinuously operative device to permit at any desired moment accurate control of the amplified frequency or any other characteristic of the circuit.

One of the difficulties encountered in dial illumination is that the dial lamp requires a relatively large amount of current which not only weighs heavily on the life of the voltage source or battery in battery-supplied amplifier circuits but also, when switched on, is liable to produce a voltage drop deteriorating the quality and quantity of amplification.

A specific object of this invention is an audio amplification stage including several electron paths arranged in parallel, each path being fed by a filament. The filaments are arranged in parallel to a source of voltage such as a storage battery. One of the filaments, or a portion thereof which is dimensioned to be excited by the same voltage as the dial lamp, is connected in parallel to this dial lamp. A push-button switch permits the selective replacement in circuit of this filament or filament portion by the dial lamp and, conversely, the replacement in circuit of the dial lamp by the filament or filament portion.

Since the audio amplifier contains several stages, the interference caused by intermittently switching off an electron path, or at least a portion thereof, and its replacement by a dial lamp have been found to cause a minimum of noticeable interference with frequency and amplitude of output. The life of the battery remains practically unimpaired.

A more specific object of the invention is an audio amplifier stage comprising a single amplifier valve containing in addition to grid and anode a filament having two portions, each of these portions being connected in parallel to the voltage source. Loss in amplification in such a tube when operated with only one filament has been found to be negligible.

Another object of the invention is a radio frequency receiver comprising one or more amplification stages, the filament circuits of which are connected in parallel to a source of voltage and which includes one filament circuit connected to be selectively replaced by the filament circuit of another discontinuously operative tube, such as the oscillator tube of a crystal calibrator.

This and other objects of the invention are

2

schematically illustrated in the accompanying drawings in which:

Fig. 1 shows a diagram of part of a superheterodyne radio receiver embodying the invention as applied to a dial lamp;

Fig. 2 shows a diagram of a radio frequency receiver embodying the invention as applied to the oscillator tube of a crystal calibrator.

In Fig. 1, the incoming high frequency oscillations, if necessary after sufficient amplification (not shown), are applied to grid 1 and mixed with the oscillations produced at grid 2 of a mixer tube 3 consisting of a hexode. The anode of tube 3 is connected, in a manner not shown, to the grid of intermediate frequency amplifier 4, the output of which is detected and amplified in tube 5 and further amplified in tube 6 which has a filament consisting of two half portions 7, 8. The output of tube 6 is applied to a utilization circuit. The filaments 9, 10, 11 of tube 3, 4, 5, respectively, and the filament halves 7, 8 of tube 6 are connected in parallel to storage battery 12. This battery can have any desired voltage, e. g. 6, 12 or 24 volts. In the present example each filament is supplied by about 1.4 volts.

Connections and interconnections of tubes 3, 4, 5 and 6, which are not shown, are well known in the art and can be made in any desired manner without exceeding the scope of this invention.

Push-button switch 13 substitutes the current of dial light 14 for one of the otherwise parallel half portions 7, 8 of the filament of valve 6. In the present example, valve 6 is a tube of the 3Q4 type which has two .050 amp. filaments. The output from this tube is only very slightly reduced when one of the filament halves is not used. The dial light 14 is also rated at about 1.4 volts at .050 amps. so that when the dial light is turned "on" there is no increase in current drain through the voltage-dropping resistor 15 and, consequently, no change in filament voltage. If the filament voltage did change when the dial light was turned on, the H. F. oscillator circuit would shift in frequency as a result of the filament voltage drop. This danger is reduced to a minimum.

The invention is not limited to the circuit and circuit elements shown or described. It may be applied with equal advantage to any other type of thermionic valve circuit affording dial illumination or any other discontinuous control function.

Instead of using a twin-filament tube such as

is shown in Fig. 1, a twin-amplifier tube may be used including not only two separate filaments but also two grids and two anodes. A further alternative within the scope of this invention is the use of a tube having a filament a predetermined portion of which—not only half—can be selectively branched off and replaced through a switching operation by the filament of a dial or control tube of appropriate voltage drop.

Another alternative is the provision of several tubes, especially of two tubes in parallel or push-pull connection and the replacement of the filament of one of these tubes by the filament of a discontinuously operative tube, such as a dial lamp or any other control tube.

Fig. 2 shows diagrammatically a radio frequency receiver in which antenna 27 is coupled over transformer 28 and tuning circuit 29 to the control grid of mixer tube 30. The anode of tube 30 is connected over transformer 31 to the input circuit of an intermediate frequency amplifier 32, the output of which is fed over transformer 33, a combined detector, and first audio frequency amplifier tube 34 to a second audio frequency amplifier tube 35 which, in turn, is connected over transformer 36 to a suitable output circuit (not shown). The filaments 37, 38, 39, 40 and 41 of tubes 30, 32, 34 and 35 are connected in parallel to battery terminals +A, -A. One of the filaments, 40, constituting half of the entire filament of tube 35, is connected to battery terminals +A, -A over switch 46. The anode circuit of the intermediate frequency amplifier tube 32 is connected to the output circuit of oscillator tube 42 over oscillating circuit 43. The grid circuit of tube 42 is controlled by crystal 44 in a conventional manner. The filament 45 of oscillator tube 42 is supplied by battery terminals +A, -A over the same switch 46 which, according to its position, heats either filament 40 or filament 45, thus permitting frequency calibration without noticeably affecting the amplification of the receiver.

What I claim is:

1. In a thermionic valve circuit connected for continuous operation, a source of voltage, a number of electron-emitting means connected in parallel to the source, discontinuously operative means for controlling the operation of the circuit at the desired moment, the controlling means being connectable in parallel to the source and to one of said electron-emitting means, and switching means for selectively interchanging the controlling means for only a portion of said one electron-emitting means.

2. In a thermionic valve circuit connected for continuous operation, a source of voltage, a number of electron-emitting means connecting in parallel to the source, frequency-calibrating means connectable in parallel to the source and to one of the electron-emitting means, and switching means for selectively interchanging the frequency-calibrating means for at least a portion of said one electron-emitting means.

3. In a thermionic valve circuit, a source of voltage, a number of filaments, at least one of them consisting of two series-connected halves, each of said halves and the remainder of said filaments being connected in parallel to the source, high frequency calibrating means including a crystal-controlled oscillating tube, the tube having a filament, and switching means in one position adapted to connect the filament of the tube in parallel to the source as well as to one of said filament halves and in another position

to interchange the tube filament for the other filament half.

5 4. In a circuit according to claim 1, means controlled by audio frequency currents and controlling the electrons of at least some of the electron-emitting means.

10 5. In a circuit according to claim 1, means controlled by audio modulated high frequency oscillations and controlling the electrons of one of said electron-emitting means, including a pentagrid mixer tube having one grid for applying the audio modulated high frequency oscillations, a second grid for applying predetermined high frequency oscillations, an anode circuit for deriving high frequency oscillations of an intermediate frequency, means for amplifying the intermediate frequency oscillations, means for detecting the intermediate frequency oscillations, and means for amplifying the detected oscillations, the mixing means, the intermediate frequency amplifying means, the detecting means and the amplifying means, each having electron-emitting means connected in parallel to the source, the amplifying means including electron-emitting means only a portion of which may also be connected to the discontinuously operative control means, the latter consisting of high frequency calibrating means including an oscillator tube having a filament connectable in parallel to the source.

15 30 6. In a superheterodyne receiver, intermediate frequency amplifying means, combined detecting and audio amplifying means, audio amplifying means, each of said means including at least one electron-emitting filament, the audio frequency amplifying means including an electron-emitting filament consisting of two series-connected halves, voltage-supplying means, said filaments and each of the filament halves being connectable in parallel to said voltage-supplying means, high frequency calibrating means including crystal-controlled oscillating means having an electron-emitting filament, a push-button switch, and means including said push-button switch for selectively either connecting said latter filament to and disconnecting one of said filament halves from said voltage-supplying means, or disconnecting said latter filament from and connecting one filament half to said voltage-supplying means.

35 40 7. In a thermionic valve circuit, an amplifying valve comprising a filament having a center tap to form two halves, a control valve having a filament, a source of current connectable in parallel to each half and the control valve filament, and switching means for selectively either connecting the valve filament and disconnecting one half from the source, or disconnecting the valve filament from and connecting one half to the source.

45 55 8. In a thermionic valve circuit, an amplifying valve having a filament, a source of current, a control valve having a filament, and switching means for selectively either connecting the valve filament to and disconnecting a portion of said filament from the source, or disconnecting the valve filament from and connecting said portion to the source.

50 60 9. In a radio receiver, a valve including a filament having a center tap to form two halves, a crystal-controlled oscillator having a filament, a battery connectable in parallel to each half and the oscillator filament, and a switch for selectively either opening connection between one half and source and simultaneously closing con-

nection between oscillator filament and source, or closing connection between one half and source and simultaneously opening connection between oscillator filament and source.
